FIG. 5.

UNITED STATES PATENT OFFICE.

JESSE A. DUBBS, OF LOS ANGELES, CALIFORNIA, ASSIGNOR, BY MESNE ASSIGNMENTS,
TO NATIONAL HYDROCARBON COMPANY, A CORPORATION OF SOUTH DAKOTA.

TREATING OIL.

1,123,502.

Specification of Letters Patent.

Patented Jan. 5, 1915.

Application filed November 20, 1909. Serial No. 529,049.

To all whom it may concern:

Be it known that I, JESSE A. DUBBS, a citizen of the United States, residing in the city of Los Angeles, county of Los Angeles, and State of California, have invented certain new and useful Improvements in Treating Oil, of which the following is a specification.

This invention relates to improvements 10 in treating oil and refers more particularly to a process of subjecting the oil to heat and pressure.

Among the salient objects of the invention are to provide an improved method of 15 treating oil wherein both the vaporization and condensation take place under the pressure of the generated vapors; to provide a method which is particularly adapted for the removal of the finely divided particles 20 of water from emulsified hydrocarbon oils; to provide a method which will permit of the oil being continuously subjected to the required heat and pressure in both the still and condenser without the interruption of 25 its flow; to provide a method by which this may be safely and economically done and in general to provide an improved method of the character referred to.

A method of removing the water from 30 emulsified oil is disclosed in Letters Patent No. 890,762 granted to me June 16th, 1908.

The invention consists in the matters hereinafter described and more particularly pointed out in the appended claims.

In the accompanying drawings forming a 35 part of this specification, Figure 1 is a plan view, illustrating a form of apparatus adapted to the practice of my improvement; Fig. 2 is a view in longitudinal section, the 40 plane of section being indicated by the line II-II, Fig. 1; Fig. 3 is a detail view of a stand or cushioning pipe connected with the apparatus; Fig. 4 is a view in longitudinal section of a check valve such as may be employed at several points in the apparatus, as 45 will hereinafter be more fully described; Fig. 5 is a view in side elevation of the main cooling tank; parts which are repeated in the several figures bear the same reference 50 numerals in each case.

In the preferred apparatus for the practice of my invention, the oil is forced from the pipe line leading from the well or other source of supply, through the pipe 1, into 55 the coil 2, which may be heated to the desired temperature by any suitable means, as

for example, by arranging the coil in the heating chamber of a suitable furnace, indicated at 3. It is preferred that a check valve 4 (which may be conveniently of the structure indicated in Fig. 4) should be arranged in the pipe 1, to prevent any backward flow of oil, in case of an excessive pressure in the apparatus; and, for the protection of the apparatus, and the operation, a 60 safety valve, indicated at 5, is connected with the coil. From this preliminary heating coil 2, the oil passes into a larger coil 6, which may be heated to the desired temperature in any suitable manner, as by 65 arranging it in the heating chamber of a furnace, indicated at 7. The pipe comprising this coil is preferably of larger internal diameter than the pipe of the coil 2, so that there may be a segregation of the steam 70 (produced from the water which the oil contained) and the vapors of the more volatile constituents of the oil from the liquid portions thereof, such segregated gases or 75 vapors being conducted away from the coil 80 by means of distillation pipes 8 to the condensing coil 9, located in a receptacle 10, through which a cooling fluid is caused to flow, condensing the oil and water vapors 85 passing through the coil. From this coil 9 the condensed vapors flow into the separating 90 chamber 11, where the water and the oil are allowed to stratify, in accordance with their relative specific gravities. From this separating chamber 11, the condensed 95 hydrocarbons are carried away by the pipe 12, and the condensed steam is drawn off from time to time through the outlet 13. For convenience in determining the relative 100 amounts of oil and water in the tank 11, a glass tube 14 is connected thereto, preferably through the cock 13, and extends up a suitable height along the tank. From the coil 6 the treated oil (relieved of the substantial part of the burden of water which 105 the untreated oil carried in finely divided particles) flows, by the pipe 15 into a cooling coil 16, arranged in a tank 17, where it may be subjected to the action of a cooling fluid, and from this cooler the oil flows by 110 the pipe 18 to a suitable receptacle 26, where a stratification of the oil and the small amount of water remaining may occur. Such gravity separators are well known to the art, and my invention has nothing to do 115 with the specific construction of this piece of apparatus.

Pyrometers, which may be of ordinary type, and whose positions are indicated at 19, 20 and 21 are provided, one intermediate the preliminary heater and the main heater, 5 another in the outlet pipe 15 from the main heater, and another in the outlet pipe 18 from the cooler. By means of these pyrometers, the operator may ascertain whether he is maintaining the proper temperatures 10 at various points in the apparatus. The pipe 12 leading from the separating tank 11 may conveniently be connected to the outlet pipe 18 from the cooler 17, so that the condensed vapors from the tank 11 or products 15 floating on the water in the tank may mingle with the treated oil on its way from the cooler to the stratifying receptacle 26; in that receptacle, whatever traces of water may remain in the oil flowing in pipe 15 from coil 6, and whatever traces of water 20 may remain in the distilled oil flowing in pipe 12 are practically removed.

In order to maintain the desired pressure 25 within the system, including the condenser 9 and separating chamber 11, a throttle valve 22 of any suitable form or construction may be located in the outlet pipe 18, at a point beyond the connection of the pipe 12 therewith. By properly adjusting this 30 valve 22 to the pressure under which oil enters the apparatus, any required pressure may be maintained. Check valves 24 and 25 (which also may be of the construction indicated in Fig. 4) are preferably introduced 35 in pipes 12 and 18 which lead from separator 11 and from cooler 17.

In order to prevent injury to the apparatus, cushioning means are employed, preferably located at different points in the 40 coil 2 for the preliminary heating of the oil as in such coils the hammer blows would be more apt to originate. These cushioning devices preferably consist of stand pipes 23 of suitable height. The stand pipes may be 45 made of a height greater than that at which the liquid would stand for the pressure in the apparatus, so that in the case of a hammer blow these liquid columns will form a yielding cushion; or, preferably, as indicated 50 in Fig. 3, the stand pipes 23 are closed at the top and a body of inclosed air affords the cushioning effect desired. In treating these emulsion oils the heat and pressure to 55 which the oil is subjected to effect a separation of the water and oil will be approximately proportional to the manner in which the oil and water are mixed, *i. e.*, whether the globules of water are large or small and also to the percentage of water contained in 60 the oil. If the globules are small, or if the percentage of water is large the heat or pressure or both should be increased. As for example, in oil containing about 28% 65 of water (which is the case of oil of the Santa Maria field of California), a pressure

of about 25 pounds, and a temperature of 325° F., more or less, has given very good results, as regards the segregation of the water, although I have performed my operation under pressures ranging from three to 70 two hundred and fifty pounds above atmospheric. As the oil is maintained above the vaporizing point of water, and as an opportunity is afforded in the large coil 6 for a separation of the water vapors, it will be 75 observed that a large percentage of the water will be converted into vapor and condensed together with the vapors of the more volatile constituents of the oil, in the condenser 9. Both the oil and water vapors are 80 condensed simultaneously and then flow into the separator where a gravity separation of the two will occur.

The apparatus is so constructed that the oil may be subjected to the required heat 85 and pressure without interruption of the flow.

I claim as my invention—

1. An improvement in the art of treating emulsified oil consisting in removing from a flowing body of such oil its finely divided particles of water in and by a continuous process which consists in heating the oil in a receptacle from which is excluded at all times an externally obtained pressure medium, and both vaporizing and condensing the vapors under pressure in excess of atmospheric, said pressure being produced by the vapors generated from the oil under treatment. 95

2. An improvement in the art of treating emulsified hydrocarbon oil containing at least 5% of water, consisting in removing from a continuously supplied body of such oil its finely divided particles of water in 105 and by a continuous process which consists, in submitting successive portions of the oil to a temperature above that required for boiling water at the pressure obtained and condensing the vapors thus produced, both 110 the vaporization and condensation taking place under pressure in excess of atmospheric, such pressure being produced solely by the vapor generated from the oil under treatment. 115

3. As an improvement in the art of treating emulsion oil, the method, herein described, of removing from a flowing body of such oil its finely divided particles of water, in and by a continuous operation, 120 which consists in submitting the flowing stream to a pressure in excess of atmospheric, submitting such pressure-sustaining portion of the stream to a temperature required for boiling water at such pressure, 125 separating from the flowing stream the distillate so produced, submitting the distillate to a gravity-separating operation, restoring to the main stream the floating product of such gravity-separation, and submitting the 130

united bodies to a second gravity-separating operation.

4. The method, herein described, of removing from a stream of emulsion oil, as it flows, its finely divided particles of water, such method consisting of subjecting a portion of the flowing stream to a pressure in excess of atmospheric pressure, causing the pressure-sustaining portion of the flowing stream to pass, first through a relatively constricted conductor, and then through a relatively large conductor, raising the temperature of the constricted stream to a point approximating the boiling point of water, bringing the temperature of the enlarged stream to the boiling point of water under such pressure and then successively relieving such stream, first of its excess temperature, and second of its excess pressure, and submitting the oil, as it flows, to a gravity-separating operation.

5. The herein described method of removing the finely divided particles of water from emulsified pitch-yielding hydrocarbon oils, containing five per cent. of water or more, which consists in subjecting a body of such oil to a pressure above atmospheric, producing said pressure by heating said oil to a temperature above that required for boiling water at said pressure, and during said treatment removing the steam and oily vapors generated.

6. The herein described method of removing the finely divided particles of water from emulsified pitch yielding hydrocarbon oil containing at least 5% of water, which consists in subjecting a body of such oil to a pressure above atmospheric, said pressure being produced by heating the oil to a temperature above that required for boiling water at said pressure, permitting the products volatilized from the oil to pass freely to a condenser and subjecting said volatilized products while under their self-imposed pressure to the action of said condenser.

7. The herein described method of removing the finely divided particles of water from emulsified pitch yielding hydrocarbon oil containing at least 5% of water, which consists in subjecting a body of such oil to a pressure above atmospheric, said pressure being produced by heating the oil to a temperature above that required for boiling water at said pressure, permitting the products volatilized from the oil to pass to a condenser, and subjecting said volatilized products while under their self-imposed pressure to the action of said condenser and regulating the pressure exerted by said volatilized products by controlling the discharge from the condenser.

8. The herein described process of treat-

ing hydrocarbon oil which consists in subjecting a body of such oil in a receptacle to 65 a pressure materially above atmospheric, said pressure being produced by the products volatilized from the oil under treatment in the heating of the oil to a temperature above that required for vaporizing 70 water at the operating pressure, permitting the generated vapors to pass continuously from said receptacle to a condenser and subjecting such vapors to the action of the condenser while under their self-imposed pressure above atmospheric, unaided at all times by extraneous gaseous pressure.

9. The herein described process of treating hydrocarbon oil which consists in subjecting such oil in a receptacle to a temperature in excess of 300° F., permitting the volatilized products generated from the oil under treatment to pass freely to a condenser where they are condensed, and maintaining substantially the entire pressure exceeding ten pounds to the square inch in 80 both the receptacle and condenser during the whole process solely by the vapors generated from the material under treatment.

10. The herein described process of treating hydrocarbon oil, which consists in subjecting a body of such oil in a receptacle having a space above the liquid to a pressure in excess of atmospheric, obtaining substantially the entire pressure desired by 95 the products volatilized from the oil under treatment by the heating of the oil, substantially the entire space above the liquid in the receptacle being occupied during the whole process solely by said volatilized 100 products, and subjecting said volatilized products while under their self-imposed pressure above atmospheric to a condensing action.

11. An improvement in the art of treating 105 hydrocarbon oil by heating and distilling the products volatilized therefrom, under pressure effected by the volatile constituents of said liquid, consisting in supplying the oil to a container, heating it for causing volatilization, confining the volatilized constituents in the presence of the oil for causing a pressure thereon materially exceeding atmospheric, continuously passing the volatilized products to a condenser and effecting condensation thereof under their self-imposed pressure, and controlling the pressure on the oil by regulating the discharge 110 from the condenser.

In testimony whereof, I have hereunto set 120 my hand.

JESSE A. DUBBS.
